UNITED STATES PATENT OFFICE.

ERASTUS E. WINKLEY, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

HEEL-BREASTING MACHINE.

1,344,782.

Specification of Letters Patent. Patented June 29, 1920.

Application filed December 16, 1916. Serial No. 137,369.

To all whom it may concern:

Be it known that I, ERASTUS E. WINKLEY, a citizen of the United States, residing at Lynn, in the county of Essex and State of Massachusetts, have invented certain new and useful Improvements in Heel-Breasting Machines; and I do hereby declare the following to be a full, clear, and exact description of the invention, such as will enable others skilled in the art to which it appertains to make and use the same.

This invention relates to a machine for shaping the breast-surface of the heel of a boot or shoe, particularly at the point where the breast-surface joins the shank of the shoe-sole.

The general object of the invention is to produce a machine, for the said operation, which shall perform its work rapidly and accurately and without the necessity of great skill or care on the part of the operator. A more particular object of the invention is to produce a machine for shaping the concave surface of a French heel, so as to produce a smooth blending of this surface with that of the shoe-sole, and especially to accommodate the operation of the machine to the transverse convexity of the shank of the sole.

A feature of the invention contemplates the provision in a heel-breasting machine of cutting means adapted to act on the heel breast of a shoe having a French heel, and means for tilting and cutting means transversely of the shoe to shape the heel breast to transverse convexity of the shank of the shoe. Preferably the cutting means is capable of shaping the heel breast longitudinally of the heel as well as to the transverse convexity of the shank of the shoe, so that the desired shaping of the heel breast may be accomplished in a single operation. In the preferred embodiment of the invention flexible cutting means is employed which may comprise a pair of rotary cutters arranged to operate simultaneously upon opposite sides of the heel breast of a shoe, and means is provided for changing the angular relation of the paths of motion of the cutters. The broader features of the invention, however, are not limited to a machine employing flexible cutting means and, except as defined in the claims, the invention

is not limited to a machine for operating upon French heels.

Other features of the invention comprise certain constructions, arrangements and combinations of parts hereinafter described and claimed, the advantages of which will be obvious to those skilled in the art.

In the accompanying drawings Figure 1 is a plan-view of a machine embodying the present invention, together with a shoe upon which the machine is shown as operating. Fig. 2 is a front-elevation of the upper part 65 of the machine, with the operative instrumentalities in a different position from that of Fig. 1. Fig. 3 is a sectional view on the line 3—3 in Fig. 1, but on a much larger scale. Fig. 4 is a vertical section on the 70 line 4—4 in Fig. 1, but on a smaller scale. Fig. 5 is a perspective view of one of the cutters; and Fig. 6 is a perspective view of the expanding bushing by which the cutter is fixed to the cutter-shaft.

The invention is illustrated as embodied in a machine having two rotary cutters 10, which are fixed at the inner ends of two cutter-shafts 12. These shafts turn in bearings 14 (Fig. 3), which are supported in 80 two sleeves 16 and 18 at the front of the machine.

The sleeves 16 and 18 are supported with their axes always in a common vertical plane, but are arranged to be moved pivotally about the axis of a shaft 20 extending in a fore-and-aft direction, normal to said plane. For this purpose the sleeve 16 is formed integrally upon a yoke 22, which has bearing-sleeves 24 and 26 loosely embracing 85 the shaft 20. The sleeve 18 is likewise integral with a yoke 28, having bearing-sleeves 30 and 32 which embrace the shaft 20. The shaft is mounted in bearings at the upper ends of uprights 34 and 36, which 90 constitute part of the frame of the machine. 95

The cutter-shafts and cutters are rotated constantly, during the operation of the machine, by means operative regardless of the pivotal movements of the yokes 22 and 28. 100 The shaft 20 is employed as a part of the actuating means, and for this purpose it is provided with a gear 38 which meshes with a pinion 40 driven by a pulley 42. This pulley rotates loosely upon a shaft 44 which is 105 fixed in the frame of the machine. An

idler or loose pulley 46 is mounted alongside the driving-pulley 42, and these pulleys are adapted to receive a belt from any suitable source of power. A belt-ship-
5 per 48 is used for shifting the belt from one pulley to the other in the usual manner.

The countershafts 50 and 52 are journaled in transverse bearing-sleeves 54 and 56 on the yokes 22 and 28, respectively. These
10 countershafts carry skew-gears 58 and 60, which mesh with corresponding gears 62 and 64, respectively, fixed on the drive-shaft 20. The countershafts and cutter-shafts are provided, at their outer ends, with sprocket-
15 wheels which are connected by chains 66 and 68, so that the cutter-shafts are driven by the respective countershafts and both in the same direction. Each yoke is provided with an adjustable idler-wheel 70 engaging the
20 corresponding chain to adjust the tension of the latter.

It will be apparent that either yoke may be swung about the axis of the drive-shaft 20 without disturbing the coöperative relation of the corresponding skew-gears, so that the cutters are rotated constantly regardless of the angular relation of their axes of rotation.

The yokes 22 and 28 are so controlled as
30 always to have equal inclination from horizontal position, and to be moved in unison through a sufficient angle to accommodate the cutters to the lateral inclination or convexity of the shank of the shoe-sole. For
35 this purpose each yoke is provided with a depending arm 72, and these arms are connected, by two links 74, with a slide-block 76 which moves vertically in a bearing on the frame of the machine. The head-frame
40 is mounted upon a hollow column 78, and at the lower end of this column is pivoted a treadle-lever 80 by which the inclination of the cutters is controlled. The slide block 76 is connected with the treadle-lever by a rod
45 82, so that when the treadle is depressed the arms 72 are swung downwardly, thus swinging the cutter-shafts, from their normal horizontal alinement, to oppositely inclined positions, as shown in Fig. 2. A spring 84,
50 connected to the treadle-lever, normally retains it in raised position, and returns it to such position when pressure upon the treadle-lever is released. The downward movement of the treadle-lever is limited by means
55 of a rod 88 which is pivoted, at its lower end, to the lever, and which slides through a sleeve 86 threaded into a lug on the column 78. Stop-nuts 90 on the rod 88 engage the upper end of the sleeve 86 and thus arrest the downward movement of the treadle-lever at a point which may be adjusted by screwing the sleeve or the stop-nuts upwardly or downwardly.

Each cutter, as shown in Fig. 5, comprises a blade of the form of a hollow semi-

cylinder sharpened on one edge. The cutter is also provided with a shank-portion 94 in the form of a cleft hollow cylinder. As shown in Fig. 3, the cutter-shaft 12 has a cylindrical shell 92, formed integral at its 70 inner end, and the shank 94 of the cutter is fitted within this shell. A cleft bushing 96 fits within the shank 94, and the parts are secured in place by a screw 98 which is threaded into the shaft and which has a 75 conical head 100 fitting the conical bore of the bushing 96. When the screw is driven home the bushing is expanded, and it expands the shank 94 of the cutter so that the latter is clamped securely within the shell 80 92. The cutter may be readily removed for sharpening upon backing off the screw 98.

Associated with each cutter is a guard 102 which curves over the upper and forward part of the cutter, and which is fixed 85 to the corresponding bearing-sleeve. The upper and lower edges of the guard constitute gages which are adapted to bear against the breast-surface of the heel and the shank-surface of the shoe-sole and thus to determine 90 the position of the concave surface shaped by the cutter. The guard also prevents the material removed by the cutter from being thrown against the operator, and prevents injury to the operator through 95 accidental contact with the cutters.

In the normal position of the parts the cutters are in axial alinement, as shown in Figs. 1 and 4. With the parts in this position the operator, standing in front of the 100 machine, presses a shoe against the cutters, as in Figs. 1 and 4, and draws the shoe upwardly and forwardly until the edges of the guard are engaged with the heel-breast and the shank of the shoe-sole, thus indicating 105 that the cutter has trimmed the concave part of the breast-surface to the required depth. Holding the shoe in this position the operator then depresses the treadle, thus rocking the cutters to the position shown in 110 Fig. 2. By this movement the cutters are caused to complete the heel-breasting operation to the lateral margins of the sole, notwithstanding the transverse convexity of the sole. The relation of the parts is such 115 that the axis of this pivotal movement, which is the axis of the shaft 20, coincides with the lowermost parts of the adjacent extremities of the cutters, as shown in Fig. 2, so that these extremities do not interfere 120 with each other during this angular movement. The trimming operation is completed as just described, and the operator then releases the treadle and removes the shoe from the machine. The stop-device 125 connected with the treadle-lever is preferably adjusted so as to permit only the degree of angular movement of the cutter-shafts necessary for the particular style of shoe on which the machine is to operate. 130

The machine of the present application produces an accurate formation of the heel-breast from one lateral extremity to the other, regardless of the transverse convexity 5 of the sole, and in the specific embodiment shown, in which the cutters are adapted for shaping a concave heel-breast on a French heel, this breast is so formed as to merge smoothly into the surface of the shoe-sole, 10 the trimmed part of the heel-breast having the form of a surface warped about two different axes, this surface being more regular than that which is produced by the ordinary method of breasting a French heel, 15 wherein the operation of a single rotary cutter is controlled wholly by the skill of the operator. In the present machine, not only is the operation controlled automatically, by the gaging devices and the means 20 for angularly adjusting the cutters, so as to dispense with the necessity of a skilled operator, but by the use of two cutters, operating simultaneously on opposite sides of the heel-breast, the operation of the machine 25 is rendered very rapid, requiring little more time than is necessary to properly engage the shoe with the cutters and depress the treadle.

Having thus described the invention, and 30 the preferred manner of practising it, it is definitely stated in its true scope in the following claims.

What is claimed as new is:

1. A heel-breasting machine having, in 35 combination, two cutters arranged to operate simultaneously on opposite sides of the heel-breast of a shoe; and means for actuating the cutters in angularly related paths of motion.

40 2. A heel-breasting machine having, in combination, two cutters arranged to operate simultaneously on opposite sides of the heel-breast of a shoe; means for actuating the cutters in angularly related paths of motion; and means for changing the angular 45 relation of said paths of motion.

3. A heel-breasting machine having, in combination, two rotary cutters arranged close together so that they may be engaged 50 simultaneously with the heel-breast of a shoe; and means for supporting and rotating the cutters upon axes inclined to each other.

45 4. A heel-breasting machine having, in combination, two rotary cutters arranged close together so that they may be engaged simultaneously with the heel-breast of a shoe; means for supporting and rotating the cutters on axes lying in the same plane; and means for changing the angular 60 relation of the axes to each other.

5. A heel-breasting machine having, in combination, two rotary cutters arranged close together so that they may be engaged 65 simultaneously with the heel-breast of a

shoe; and means for changing the angular relation of the cutters about an axis intersecting the plane of the heel-breast and coinciding approximately with adjacent points on the working surfaces of the two 70 cutters.

6. A heel-breasting machine having, in combination, two yokes pivotally movable about a common axis; two cutters rotatably supported by the yokes on axes lying substantially in a plane normal to the pivotal axis; means for swinging the yokes equally and simultaneously, in opposite directions, about the pivotal axis; and means for rotating the cutters regardless of such movements of the yokes.

7. A heel-breasting machine having, in combination, a rotary cutter adapted to shape the concave heel-breast of a shoe; and a gage curved about the cutter and having one edge substantially parallel to the axis of the cutter and arranged to engage the sole of the shoe, adjacent the cutter, to limit the depth of the cut.

8. A heel-breasting machine having, in combination, a rotary cutter adapted to shape the concave heel-breast of a shoe; and substantially parallel gages arranged to engage the heel-breast transversely near the top lift and the shank of the shoe adjacent 95 the cutter to determine the relation of the shaped surface to these parts.

9. A heel-breasting machine having, in combination, a rotary cutter adapted to shape the concave heel-breast of a shoe, and 100 a guard partly enveloping the cutter the opposite ends of which are substantially parallel and are located in position to engage the heel-breast and sole of the shoe and thus to determine the relation of the shaped 105 surface of these parts.

10. A heel-breasting machine having, in combination, a substantially cylindrical cutter; means for rotating the cutter about its axis; and a guard having unyielding work 110 engaging edges and arranged above and in front of the cutter but exposing its rear and lower surface.

11. A heel-breasting machine having, in combination, a substantially cylindrical cutter, means for rotating the cutter about its axis, and a guard engaging the shoe to determine the depth and curvature of the heel-breast arranged above and in front of the cutter but exposing its rear and lower 115 surface.

12. A heel-breasting machine having, in combination, a rotary cutter mounted on a cutter shaft extending transversely of the shank when the shoe is in position to be 120 operated upon, and a gage curved about the cutter and having its ends on the heel-breast and shank of the shoe.

13. A heel-breasting machine having, in combination, cutting means adapted to act 130

on the heel-breast of a shoe having a French heel, and means for tilting the cutting means transversely of the shoe to shape the heel-breast to the transverse convexity of the shank of the shoe.

14. A heel-breasting machine having, in combination, cutting means adapted to shape longitudinally the heel-breast of a shoe having a French heel, and means for tilting the cutting means transversely of the shoe to shape the heel-breast to the transverse convexity of the shank of the shoe.

15. A heel-breasting machine having, in combination, cutting means adapted to act on the heel-breast of a shoe having a French heel, means for tilting the cutting means transversely of the shoe to shape the heel-breast to the transverse convexity of the shank of the shoe, and a gage to determine the depth of the cut made by the cutting means.

16. A heel-breasting machine having, in combination, cutting means adapted to act

on the heel-breast of a shoe having a French heel, and means under control of the operator for tilting the cutting means transversely of the shoe to shape the heel-breast to the transverse convexity of the shank of the shoe.

17. A heel-breasting machine having, in combination, cutting means adapted to act on the heel-breast of a shoe having a French heel, and means for tilting the cutting means transversely of the shoe to simultaneously shape both sides of the heel-breast to the transverse convexity of the shank of the shoe.

18. A heel-breasting machine having, in combination, flexible cutting means adapted to act on the heel-breast of a shoe having a French heel, and means for flexing the cutting means to shape the heel-breast to the transverse convexity of the shank of the shoe.

ERASTUS E. WINKLEY.

It is hereby certified that in Letters Patent No. 1,344,782, granted June 29, 1920, upon the application of Erastus E. Winkley, of Lynn, Massachusetts, for an improvement in "Heel-Breasting Machines," errors appear in the printed specification requiring correction as follows: Page 1, line 34, for the word "and" read *the*; same page, line 36, after the word "to" insert the word *the*; and that the said Letters Patent should be read with these corrections therein that the same may conform to the record of the case in the Patent Office.

Signed and sealed this 3d day of August, A. D., 1920.

[SEAL.]

R. F. WHITEHEAD,

Acting Commissioner of Patents.
